UNITED STATES PATENT OFFICE

102,336

DESIGN FOR A SHOE

Theodore Samuels, St. Louis, Mo.

Application November 14, 1936, Serial No. 65,901

Term of patent 3½ years

To all whom it may concern:

Be it known that I, Theodore Samuels, a citizen of the United States of America, residing in St. Louis, county of St. Louis, and State of Missouri, have invented a new, original, and ornamental Design for a Shoe, of which the following is a specification, reference being had to the accompanying drawing, forming part thereof.

Fig. 1 is a plan view of a shoe showing my new design.

Fig. 2 is a side elevational view of a shoe as shown in Fig. 1.

I claim:

The ornamental design for a shoe substantially as shown.

THEODORE SAMUELS.
